United States Patent Office.

CYRUS P. GROSVENOR, OF McGRAWVILLE, NEW YORK.

Letters Patent No. 71,872, dated December 10, 1867.

IMPROVEMENT IN THE MODE OF PREVENTING EXPLOSION OF LAMPS.

The Schedule referred to in these Letters Patent and making part of the same.

TO ALL WHOM IT MAY CONCERN:

Be it known that I, CYRUS PITT GROSVENOR, of McGrawville, in the county of Cortland, in the State of New York, have invented a new and improved Mode of Preventing Explosion of Lamps, and other apparatus used for obtaining light and heat from coal-oils, alcohol, and other explosive substances, and at the same time of effecting other important objects, such as the production of better light, more heat, less smell, and more cleanliness, thus securing safety, economy, and comfort; and I do hereby declare that the following is a full and exact description thereof, reference being had to the accompanying drawings, and to the letters of reference marked thereon.

The nature of my invention consists in supplying the vacuum made in the reservoir by combustion with nitrogen gas, known to science as the flame-extinguishing or antiphlogistic gas, and in so constructing a burner as to accomplish this end, and the other objects mentioned. The burner, including the top of the lamp, I make close, so as to prevent the ingress of atmospheric air into the reservoir.

Construction.

That others may be enabled to make and use my invention, I describe its construction and operation as follows, reference being had to the drawings.

I apply my invention to any form of lamps, heaters, burners, and other appendages susceptible of it.

I construct a burner, Figure 2, of brass or other suitable material, differing from other burners in having no hole for admission of atmospheric air into the reservoir during the process of combustion. In order to this, I make the bottom plate *h* *h*, fig. 2, of the burner, with no other orifice than the one for inserting the burning-tube *i* *i*, and make the joint of this insertion air-tight by brazing or soldering, as I do all of the joints of the box containing the wheels of the wick-elevator.

To prevent the ingress of air at the places of insertion of the axis *e a*, (fig. 2 of drawings,) through which air might pass into the wheel-box *o o o o*, and descend through the tube into the reservoir, supplying the vacuum, I support the end *e* within the wheel-box by inserting it into the close socket *f*, instead of carrying it through the side, as is done in other burners. I secure against the admission of air through the hole at *e e* by applying a "packed box," *e e d*, used in machinery where air-tight insertions are required, but first used by me for the purpose here indicated. This packed box is furnished with a thumb-piece, *g*, and screw, *b*, for compressing the packing *e e* around the axis, and against that end of the box, completing the close construction.

Operation.

In the use of this close-jointed construction of the burner, the vacuum made in the reservoir by combustion cannot be supplied with atmospheric air, but must, necessarily, be supplied with nitrogen gas, resulting from combustion.

The two gases, oxygen and nitrogen, composing atmospheric air, are always separated by combustion. The oxygen, the flame-making element, being about one-fifth, ($\frac{1}{5}$) is consumed, while nitrogen, the flame-extinguishing element, being about four-fifths, ($\frac{4}{5}$) is liberated; and in the simple process of combustion carried on at the top of the tube or wick, no other contrivance being needed for this purpose, the liberated nitrogen descends, necessarily, by force of atmospheric pressure, through the interstices of the wick, in sufficient quantity to supply the gradually-extending vacuum below, even to the entire exhaustion of the fuel, when it is found that the reservoir is completely filled with this gas. Thus the continuous presence and supply of this descending gas during combustion precludes the possibility of ignition within the reservoir, and consequent explosion from the heated metals of the burner, even though their heat were to become extreme.

Of the protective nature of this gas, upon which I rely as the only means of securing lamps and other burners from explosion, where explosive substances are used, I may refer to the authority of Sir H. Davy, who says, "Sulphur may be melted, even sublimed in it, [nitrogen gas,] and phosphorus may be liquefied in it, without undergoing combustion."

By this invention, a larger amount of oxygen is forced into the flame, increasing its brightness, and diminishing the necessary consumption of fuel. Proof of this is afforded by the fact that the flame produced by my nitrogen safety-burner is more gas-like in whiteness and intensity than from open burners.

As I allow no orifice for ventilation, evaporation from within is precluded, except through the tube to the flame, where it is profitably disposed of; consequently, no coating of oil, formed by vapor condensed on the outside of the burner and lamp, can take place, exposing it to external ignition and explosion by way of any orifice.

What I claim as my invention, and desire to secure by Letters Patent, is—

The application to lamps or heaters, using coal-oils, alcohol, or other explosive substances, of such a burner as will supply the vacuum made in the reservoir by the combustion with nitrogen gas, the burner being constructed as herein described, or in any other form substantially the same, and which will produce the intended effect.

CYRUS P. GROSVENOR.
